United States Patent Office

Des. 214,472
Patented June 17, 1969

214,472

DISPLAY STAND FOR PANTS AND THE LIKE

Richard B. Friedman, Shaker Heights, Ohio, assignor to Freely, Inc., Cleveland, Ohio, a corporation of Ohio

Filed Jan. 23, 1968, Ser. No. 10,272

Term of patent 14 years

Int. Cl. D6—01

U.S. Cl. D80—9

FIG. 1

FIG. 2

FIG. 3

FIG. 4

FIG. 1 is a perspective view of a display stand for pants and the like;

FIG. 2 is a top plan view thereof;

FIG. 3 is a front elevational view thereof; and

FIG. 4 is a side elevational view thereof.

I claim:

The ornamental design for a display stand for pants and the like, substantially as shown.
